CHILD'S AUXILIARY SEAT ATTACHMENT

Arthur E. Singleton, Fort Wayne, Ind., assignor
to The Toidey Company, Gertrude A. Muller,
Inc., a corporation of Indiana

Application October 16, 1947, Serial No. 780,171

7 Claims. (Cl. 155—131)

1

This invention relates to improvements in a child's auxiliary seat attachment for an adult's toilet, in which an adjustable foot-rest is included together with locking means for securing the foot-rest in selected positions relative to the auxiliary seat.

An object of the instant invention is to provide a child's toilet seat with a foot-rest adjustably supported in connection therewith, and a locking means for the foot-rest concealed beneath the seat out of reach of the occupant but accessible for manipulation by the attendant.

Another object of the invention is to provide dual locking means for foot-rest supporting rods in a toilet seat adapted for simultaneous manipulation.

Other objects and advantages of the invention appear in the following description.

An illustrative embodiment of the invention is shown in the accompanying drawings, in which:

Fig. 1 is a side elevational view of a structure in which the invention is incorporated;

Fig. 2 is a bottom plan view of the structure shown in Fig. 1, parts being omitted; and

Fig. 3 is a fragmentary bottom plan view, drawn to an enlarged scale, showing one of the locking devices.

The illustrative embodiment of the invention consists preferably of a molded form of plastic material shaped to provide a seat 5, arm-rests 6 and a back-rest 7. The underside of the seat 5 is hollow in that it has an outer marginal downwardly extending flange 8 and an inner downwardly extending flange 9 surrounding the toilet opening 10, and in connection with the seat is arranged a foot-rest 11 supported on sliding rods 12 that have longitudinal movement through the outer marginal flange 8 and guides 13 and 14 conveniently located within the hollow seat, there being openings provided in said guides through which said rods extend, and stops 12' to limit movement thereof.

A locking mechanism is provided in the seat for each of the rods 12 whereby to prevent axial movement of the rods in either direction, one locking mechanism being the counterpart of the other. Each locking mechanism consists of an operating lever 15 having a perforated angular portion 16 through which the corresponding supporting rod 12 extends, and a perforated lock-lever 17 mounted on said supporting rod 12 provided with an angular finger or abutment 18 that has engagement with the operating lever when the latter is moved into unlocking position. The guides 13 and 14 have opposing lugs 19 and 20 between which the extension 16 and the lock-

2

lever 17 extend and are confined in operating position therebetween by staples 21 secured in said lugs. The lock-lever 17 bears against the lug 19 which constitutes a fulcrum therefor, and the outer end of the extension 16 rests upon a projection 22 of the guide 13 which constitutes a fulcrum for the operating lever.

Disposed loosely upon the rod 12, concentric therewith, is a compression spring 23 that bears oppositely against the opposing faces of the extension and lock-lever, and tends to move said extension and lock-lever into locking engagement with the corresponding rod 12. The openings in the extension and lock-lever are such as to permit freedom of movement of the rod therethrough when moved to positions at right angles thereto, and sufficiently snug as to cause binding of the extension and lock-lever upon the rod when the lock-lever is released by the operator. Thus, the foot-rest may readily be moved into selected positions when the levers are depressed, and become locked in such positions due to the reaction of the springs, when the levers are released by the operator.

The seat is equipped with a downwardly extending spring hook 24 and stops 25 by which the appliance is secured to and centered upon an adult toilet seat (not shown) as in the usual manner.

In use, the foot-rest is adjusted by first pressing the operating levers 15 toward each other, whereupon the lock-levers 17 become engaged thereby, which action causes rocking of the portions 16 and the lock-levers 17 upon their respective fulcrums 22 and 19 and compression of the springs 23 until said extensions and the corresponding lock-levers are disposed at right angles to the supporting rods 12, thus permitting the rods to be axially moved freely in either direction as may be desired while adjusting the foot-rest relative to the seat structure. Upon releasing the operating levers, the extensions thereon and the lock-levers reassume their normal locking positions by the reactionary force of the springs, thus securing the foot-rest supported on the rods in the position to which it has been adjusted.

A feature of the invention is the arrangement of the operating levers and the lock-bars in the seat and their connections with the supporting rods for the foot-rest, whereby the rods are normally locked against axial movement in the seat in either direction, or unlocked simply by simultaneously pressing the operating levers thus to permit adjustment of the foot-rest.

Variations from the particular construction

above disclosed may be resorted to by the exercise of skill in the art, without departure from the spirit or scope of the invention.

What I claim is:

1. An infant's toilet seat comprising a substantially flat base having spaced lateral sides, a pair of spaced guide flanges supported by said base on each of said sides and having aligned openings therethrough, two parallel extending rods carried by said base, a foot-rest carried on the common ends of said rods, each rod reciprocably received by the openings of a respective pair of said flanges, two locking levers supported between each pair of spaced flanges and having openings through which the respective rod is received, a spring surrounding each rod between the respective levers tending to urge the levers apart, a fulcrum provided on one of each pair of flanges and engageable by one of each pair of levers whereby each spring will urge each said one lever into locking engagement with the respective rod, and two operating portions of the other levers extending inwardly from said base sides and conjointly operable to engage and pivot said one of each pair of levers about the respective fulcrums to compress said springs and unlock said rods for movement with respect to said base.

2. An infant's toilet seat comprising a substantially flat base having spaced lateral sides, a pair of spaced guide flanges supported by said base on each of said sides and having aligned openings therethrough, two parallel extending rods carried by said base, a foot-rest carried on the common ends of said rods, each rod reciprocably received by the openings of a respective pair of said flanges, two locking levers supported between each pair of spaced flanges and having openings through which the respective rod is received, spring means carried by each rod between the respective levers tending to urge the levers apart, a fulcrum provided on one of each pair of flanges and engageable by one of each pair of levers whereby each spring means will urge each said one lever into locking engagement with the respective rod, and two operating portions of the other levers extending inwardly from said base sides and conjointly operable to engage and pivot said one of each pair of levers about the respective fulcrums to release said spring means and unlock said rods for movement with respect to said base.

3. An infant's toilet seat comprising a substantially flat base having spaced lateral sides, two parallel extending rods reciprocably carried by said base, a foot-rest supported by said rods, and locking means on said base arranged to lock said rods in a selected position and comprising guide means for each rod adapted to limit the movement of each rod to longitudinal movement only, two locking levers associated with each guide means and adapted to grip the respective rod for locking it against movement with respect to said base, each guide means providing a fulcrum for one of said levers, and means supported with respect to said base and yieldably urging said one lever into gripping engagement with the respective rod, the other of said locking levers having portions extending inwardly of said base which may be simultaneously operated to engage with said one levers respectively whereby the latter are pivoted about the respective fulcrums against the force of said yieldable means to release said rods for movement.

4. The combination with a base member, of a

5 10 15 20 25 30 35 40 45 50 55 60 65 70 75 80 85 90 95 100

rod slidably carried thereby and partially projecting therefrom, and gripping means for holding said rod in desired positions with respect to said base member; said means comprising a pair of substantially parallel guide members on said base and having aligned openings therein, a pair of levers having each an opening therein in alignment with the first mentioned openings and said rod extending through all of said openings, a spring encircling the part of said rod between said levers, one of said levers having an operating handle portion and the other lever having a projection thereon positioned to be engaged by said one lever, said guide members having means forming fulcrua for said levers positioned to cause movement of the levers by said spring to grip said rod and to permit movement of said one lever to engage the projection on said other lever and swing the latter about its fulcrum thereby overcoming the resistance of said spring and releasing the grip of the levers on the rod.

5. The combination with a base member, of a rod slidably carried thereby and partially projecting therefrom, and gripping means for holding said rod in desired positions with respect to said base member; said means comprising a pair of substantially parallel guide members on said base and having aligned openings therein, a pair of levers having each an opening therein in alignment with the first mentioned openings and said rod extending through all of said openings, a spring encircling the part of said rod between said levers, one of said levers being operable to engage an abutment on the other of said levers, said guide members having means forming fulcrua for said levers positioned to cause movement of the levers by said spring to grip said rod and to permit movement of said one lever to engage the abutment on said other lever and swing the latter about its fulcrum thereby overcoming the resistance of said spring and releasing the grip of the levers on the rod.

6. The combination with a base member, of a rod slidably carried thereby and partially projecting therefrom, and gripping means for holding said rod in desired positions with respect to said base member; said means comprising a pair of substantially parallel guide members on said base and having aligned openings therein, a pair of levers having each an opening therein in alignment with the first mentioned openings and said rod extending through all of said openings, a spring encircling a part of said rod and compressed between said levers, one of said levers having an operating handle portion and the other lever having a projection thereon positioned to be engaged by said one lever, said guide members having means forming fulcrua for said levers positioned to cause movement of the levers by said spring to grip said rod and to permit movement of said one lever to engage the projection on said other lever and swing the latter about its fulcrum thereby overcoming the resistance of said spring and releasing the grip of the levers on the rod.

7. In combination, a base member, an axially movable rod carried by said base member, a pair of spaced guide elements on said base member transversely disposed with respect to said rod and receiving said rod, a lock-lever mounted on said base member and having a portion fulcrumed on one end portion of one of said elements and having another portion engaging said rod, an operating lever also mounted on said base member and having a portion fulcrumed on the other of said

elements and having operative engagement with said lock-lever, the fulcruming portions of said levers lying on opposite lateral sides of said rod, and a compression spring disposed between said operating lever and said lock-lever arranged to urge yieldably said lock-lever into engagement with said rod, said operative engagement between said lock-lever and said operating lever occurring between abutting portions on both levers whereby movement of said operating lever in a predetermined direction will serve to move said lock-lever out of engagement with said rod, said rod thereby being movable axially on said base member.
